GUIDE TUBE

Leon Barrett, Philadelphia, Pa., assignor to
Quick-Change Carriers, Inc., a corporation of
Pennsylvania

Application April 2, 1949, Serial No. 85,169

15 Claims. (Cl. 66—126)

1

My invention relates to guide tubes, and it relates more particularly to flexible guide tubes, such, for instance, as are used in carriers for full fashioned hosiery knitting machines.

In the hosiery knitting art, the use of flexible guide tubes on carriers has proven of considerable merit; for among other advantages it permits harmless deflection of the yarn guide tube in all cases of undesired contact with an inadvertently dislodged sinker or other portion of the knitting apparatus. Suitable flexible guide tubes have been difficult to provide, however. Thus, in cases where a flexible guide tube comprises a helix formed of ordinary round wire, giving merely a line contact between adjacent convolutions, the jarring of the carrier at the end of each course-laying stroke may tend to cause vibration in the guide tube, resulting in undesired variation in the paying out of the yarn. Moreover, by the use of such wire, the flexibility is more or less uncontrolled and again variation in the paying out of the yarn may result.

On the other hand, flexible guide tubes comprising a helix made of a usual form of flat ribbon wire, while tending to be more rigid, may still prove of less than optimum satisfaction, for when deflection occurs, the spiral may open and receive a portion of the yarn, and pinch said yarn on closing. In order to avoid this difficulty, flexible guide tubes have been invented, whereby alternate helices of flat and round wire are used. Such guide tubes result in greater flexibility and a lessening of the tendency to pinch the yarn between adjacent coils. Nevertheless, they are difficult to make, and on occasion have been known to become dislodged so as to fail properly to return from their deflected position.

It is an object of my invention therefore, to provide a flexible guide tube which will safely deflect upon undesired contact with an object in the path of its travel, and which will immediately return to its original position upon being freed from said object, without pinching or cutting the yarn or other substance being guided therethrough.

Another object of my invention is to provide a flexible guide tube so constructed as to dampen any tendency to vibrate when its carrier is struck, as for instance, when it impinges against a limiting stop at the end of its course-laying stroke.

A further object of my invention is to provide a flexible guide tube which is simple and inexpensive to manufacture, safe in use, easy to install and remove, is wear-resistant and which will be of minimum thickness at its discharge end.

Other objects will be apparent from the de-

2

scription and claims which follow, as well as from an examination of the drawings.

With the above and other objects in view, my invention consists of a flexible guide tube comprising a substantially flat ribbon having a chamfered edge, and formed into a helix with the chamfered edge of one convolution substantially juxtaposed to an edge of the next convolution; an inlet conduit disposed at the inlet portion of said flexible guide tube; and an outlet conduit disposed at the outlet portion of said flexible guide tube; said inlet conduit comprising a shoulder adapted to cover the inlet terminus of said ribbon; and said outlet conduit comprising a shoulder adapted to cover the outlet terminus of said ribbon, and also comprising a channel extending from the interior of said helix to an outlet port substantially beyond said outlet terminus; the external diameter of said conduit adjacent said outlet port being substantially less than the external diameter of said helix, and said inlet and outlet conduits being in spaced relation to each other.

For the purpose of illustrating my invention, I have shown in the accompanying drawings forms thereof which are at present preferred by me, since the same have been found in practice to give satisfactory and reliable results, although it is to be understood that the various instrumentalities of which my invention consists can be variously arranged and organized and that my invention is not limited to the precise arrangements and organizations of the instrumentalities as herein shown and described.

Referring now to the drawings, in which like reference characters indicate like parts:

Figure 1 represents a perspective view of a full-fashioned hosiery knitting machine carrier holding a flexible guide tube embodying my invention.

Figure 2 represents an enlarged, vertical sectional view of a flexible guide tube embodying my invention, showing the same in mounted relation to the yarn guide tube-holding end of the carrier shown in Figure 1.

Figure 3 represents a sectional view taken generally along the lines 3—3 of Figure 2.

Figure 4 represents a fragmentary sectional view of a portion of a flexible guide tube embodying my invention, showing the same in fully deflected condition during yarn-guiding operation.

Figure 5 represents a fragmentary sectional view of the same portion of flexible guide tube as illustrated in Figure 4, but showing the relationship of parts and yarn during the recoiling operation after release from deflection.

Figure 6 represents a fragmentary sectional view of the same portion of flexible guide tube as illustrated in Figures 4 and 5, but showing the

relationship of parts and yarn when the tube has fully recovered from its deflected condition, and after release therefrom.

For purposes of illustration only, I have shown the flexible guide tube of my invention, in conjunction with a full-fashioned hosiery knitting machine carrier, although it is to be understood that it is not limited thereto, and is capable for use with other machines or other carriers, as well as for guiding other materials than yarn, 10 without departing from the spirit or essential attributes of my invention.

Thus, according to my invention, I provide a flexible guide tube 10 adapted to be carried, substantially at one end 11 thereof, by a carrier 12 having jaws 13 and 14 adapted yieldably to grip said end 11 of said flexible guide tube 10. The carrier 12 comprises an upper base portion 15 adapted to be secured to a suitable portion of the knitting machine (not shown). A suitable 20 yarn guide channel 16 may be formed along the upper face 17 of the carrier 12, operably to lead the yarn 18 therealong and into proper position for entrance into the inlet portion 19 of the yarn guide tube 10.

The yarn guide tube 10 preferably comprises a steel ribbon wire 20 formed about a helix with a single ribbon forming adjacent convolutions. The cross section of said ribbon wire 20 is preferably polygonal, and in a desired form of my invention comprises substantially a rectangle with one corner 21 thereof chamfered; and said chamfered corner being adjacent an edge 22 and an internal face 23 of the convolution 24. The external face 25 of the polygon may be substantially parallel to the internal face 23, and the unchamfered edge 26 is preferably perpendicular to the external face 25, and parallel to the edge 22.

It will thus be found that successive convolutions 24, 27, 28 and 29, etc. formed of ribbon of the cross-section described, provide a tube of substantially smoothly continuous exterior 30, and substantially interrupted interior 31, while the adjacent convolutions 24, 27, 28, etc. bear against one another along a respective area contact 32, 33, 34, etc. The effect in operation, of this construction will be more fully described hereinafter.

An inlet conduit 35 is preferably disposed at the inlet end of the guide tube 10, and comprises a mandrel 36 having an external diameter substantially equal to the internal diameter of the helix 37 formed of the wire 20, and an outer flange 38 having a shoulder 39 adapted to bear against, and to cover, the inlet end 40 of the ribbon 20. The external diameter of the flange 38 is preferably substantially equal to the external diameter of the helix 37. The outer face 41 of the flange 38 is preferably smooth. The mandrel 36 preferably comprises an axial, smooth channel 42 opening at one end on the outer face 41, and at the other end into the flexible interior of the helix 37. The outer and inner edges, 43 and 44 respectively, of the channel 42 are preferably smoothly rounded.

An outlet conduit 45 is preferably disposed at the outlet end of the guide tube 10; and comprises a mandrel 46 of an external diameter substantially equal to, or slightly greater than the internal diameter of the helix 37. The inlet end or port 47 and the outlet end or port 48 of the conduit 45 are preferably smoothly rounded, and lead to the smooth, axial channel 49 extending therebetween. Substantially radially outwardly

projecting from the conduit 45, and intermediate the inlet and outlet ends, 47 and 48, is a flange 50 having an external diameter substantially equal to the external diameter of the helix 37. The rearward face 51 of the flange 50 is preferably perpendicular to the axis of the conduit 45, and is preferably joined to the outer face of the rearward portion 52 of the mandrel 46 by a circularly concave portion or track 53. The forward portion 54 of the conduit 46 extends from the outlet end 48 rearwardly to the flange 50 to which it is preferably joined by a chamfered edge 55.

In practice, the inlet mandrel 36 preferably extends interiorly of the helix 37 a distance of two or more convolutions. In similar manner, the rear portion 52 of the outlet mandrel 46 preferably extends interiorly of the helix 37 a distance of at least more than one convolution.

The jaws 13 and 14 preferably have formed therebetween, a hollow cylindrical channel 60 of configuration substantially equal to the external periphery of the flexible guide tube 10, when said jaws are slightly spread.

In operation, the jaws 13 and 14 of the carrier 12 are spread, as by any suitable instrument (not shown), and the flexible guide tube 10 is inserted therebetween, with the inlet mandrel portion 36 adjacent the jaws 13 and 14, and said jaws are then released until they grip said inlet end, bearing against the convolutions 56, 57 surrounding the mandrel 36 and forcing them thereagainst, thereby augmenting the normal spring pressure of said convolutions against said mandrel 36. In a preferred use of my invention, the flange 38 is disposed outside the path of the jaws 13 and 14, although my invention will work even if said jaws bear thereagainst.

In the carrier illustrated in Figures 1 and 2, the external ends 58 and 59 respectively of the jaws 13 and 14 are curved away from the flexible guide tube 10 so as to allow for deflection of the tube. Moreover, the tube 10 extends beyond the region of the ends 58 and 59 of the carrier, a substantial distance, and the outlet end 54 of the tube 10 is of substantially less diameter than the thickness of the carrier jaws 13, 14. Thus, the flexible guide tube of my invention makes it possible to utilize a plurality of carriers in the closest possible relation to the sinkers, without interfering with each other.

As seen in Figure 2, the guide tube is fixed with respect to itself, in those portions thereof where the helix 37 embraces the channeled mandrels 36 and 46, and is flexible at all portions thereof intermediate said channeled mandrels 36 and 46. Moreover, an unbroken outer face 30 is presented, whereas the interior of the flexible portion is broken by the continuous helical chamfer 21 presenting a series of stages 61, 62, 63, etc. Thus, in cases of jarring the carrier 12 at the end of a course-laying stroke, whereas a harmonic period of vibration could have been established between the vibration of the exterior face 30 and the interior face 31 if such interior face were continuous and unbroken, it is substantially impossible to establish such a period of vibration with the broken interior face 23. Instead, by means of my invention each convolution of the interior face 23 serves to dampen any tendency of the exterior face 30 to vibrate. As a result, extraneous movement of the outlet tube 45 from jarring or other vibration, is inhibited; and the yarn is laid true to course.

Moreover, when the guide tube 10 is deflected

as by contact with an object disposed in its path, the circularly concave juncture between the flange 59 and the mandrel 46 permits flexing of the convolutions on the mandrel without binding. In the course of deflection, various of its convolutions will be separated, as illustrated in Figure 4; nevertheless, the yarn 18 passing through the guide tube 10 will not be caught between the convolutions. This is so because the perpendicular edge 64 at one end of a convolution 27, holds the yarn within the interior 31 of the guide tube 10; whereas the chamfered edge 21 of the next succeeding convolution 24 recedes from the yarn 18 and provides a non-cooperating surface with respect to the perpendicular edge 22 of the convolution 27. Thus, as the convolutions 24 and 27 recoil back toward undeflected condition, as for instance illustrated in Figure 5, the chamfer 21 does not cooperate with the normal edge 22 to pinch the yarn 18 therebetween. Instead, the chamfered edge 21 cams the yarn 18 away from its edge 26 and into the interior 31 of the guide tube 10. Thus, in practice, as the deflected guide tube 10 recoils back to normal undeflected position, the yarn 18 is guided free of pinching contact between the separated convolutions 24 and 27, thereby enabling it to continue to be paid out in normal course-laying operation through the guide tube 10.

I am aware that the invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

Having thus described my invention, what I claim as new and desire to obtain by Letters Patent is:

1. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution; an inlet conduit disposed at an inlet portion of said helix; and an outlet conduit disposed at an outlet portion of said helix; said inlet conduit comprising a shoulder adapted to cover at least a portion of the inlet terminus of said ribbon; and said outlet conduit comprising a shoulder adapted to cover at least a portion of the outlet terminus of said ribbon, and also comprising a channel extending from the interior of said helix to an outlet port substantially beyond the outlet terminus of said helix; the external diameter of said outlet conduit adjacent said outlet port being less than the external diameter of said helix; and said inlet and outlet tubes being in a spaced relation to each other.

2. A flexible guide tube comprising a substantially flat ribbon having substantially parallel

longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution; and an outlet conduit disposed at an outlet portion of said helix; said outlet conduit comprising a shoulder adapted to cover at least a portion of the outlet terminus of said ribbon, and also comprising a channel extending from the interior of said helix to an outlet port substantially beyond the outlet terminus of said helix; the external diameter of said outlet conduit adjacent said outlet port being less than the external diameter of said helix.

3. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution; and an outlet conduit disposed at an outlet portion of said helix; said outlet conduit comprising a channel extending from the interior of said helix to an outlet port substantially beyond the outlet terminus of said helix.

4. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution; an inlet conduit disposed at an inlet portion of said helix; and an outlet conduit disposed at an outlet portion of said helix; said outlet conduit comprising a channel extending from the interior of said helix to an outlet port substantially beyond the outlet terminus of said helix; and said inlet and outlet tubes being in a spaced relation to each other.

5. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution; an inlet conduit disposed at an inlet portion of said helix; and an outlet conduit disposed at an outlet portion of said helix; said outlet conduit comprising a channel extending from the interior of said helix to an outlet port substantially beyond the outlet terminus of said helix; the external diameter of said outlet conduit adjacent said outlet port being less than the external diameter of said helix; and said inlet and outlet tubes being in a spaced relation to each other.

6. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution; an inlet conduit disposed at an inlet portion of said helix; said inlet conduit comprising a shoulder adapted to cover at least a portion of the inlet terminus of said ribbon.

7. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution.

8. A flexible guide tube comprising a substantially flat ribbon having substantially parallel longitudinal edges, a guide face and an outer face, said ribbon being formed into a helix having a plurality of convolutions with said guide face

5 defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution; a mandrel disposed within said helix and radially supporting at least a portion thereof; and a channel disposed through said mandrel and in communication with at least a portion of said first-mentioned channel.

9. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution; a mandrel disposed within said helix and radially supporting at least a portion thereof; and a channel disposed through said mandrel and in communication with at least a portion of said first-mentioned channel; a shoulder projecting from said mandrel and covering at least a part of a terminus of said ribbon.

10. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution; a mandrel disposed within said helix and radially supporting at least a portion thereof; and a channel disposed through said mandrel and in communication with at least a portion of said first-mentioned channel; a shoulder projecting from said mandrel and covering at least a part of a terminus of said ribbon; and an outlet conduit disposed at an outlet portion of said helix; said outlet conduit comprising a shoulder adapted to cover at least a portion of the outlet terminus of said ribbon, and also comprising a channel extending from the interior of said helix to an outlet port substantially beyond the outlet terminus of said helix.

11. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution; a mandrel disposed within said helix and radially supporting at least a portion thereof; and a channel disposed through said mandrel and in communication with at least a portion of said first-mentioned channel; a shoulder projecting from said mandrel and covering at least a part of a terminus of said ribbon; and an outlet conduit disposed at an outlet portion of said helix; said outlet conduit comprising a shoulder adapted to cover at least a portion of the outlet terminus of said ribbon, and also comprising a channel extending from the interior of said helix to an outlet port substantially beyond the outlet terminus of said helix; the external diameter of said outlet conduit adjacent said outlet port being less than the external diameter of said helix; and said inlet and outlet tubes being in a spaced relation to each other.

12. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution; and an outlet conduit disposed at an outlet portion of said helix; said outlet conduit comprising a flange substantially radially projecting from said conduit intermediate the ends thereof.

13. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion,

and the next succeeding guide face portion substantially extending from said chamfered edge portion substantially to the next succeeding longitudinal edge portion of said last-mentioned convolution; and an outlet conduit disposed at an outlet portion of said helix; said outlet conduit comprising a flange substantially radially projecting from said conduit intermediate the ends thereof; a mandrel portion disposed between said flange and one of said ends of said conduit; and a track disposed between said flange and said mandrel and adapted to permit flexing movement thereon of an end convolution of said helix.

14. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; the longitudinal contour of said inner channel consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution; and an outlet conduit disposed at an outlet portion of said helix; said outlet conduit comprising a flange substantially radially projecting from said conduit intermediate the ends thereof; a mandrel portion disposed between said flange and one of said ends of said conduit.

15. A flexible guide tube comprising a substantially flat ribbon having substantially parallel longitudinal edges, a guide face and an outer face, said ribbon being formed into a helix having a plurality of convolutions with said guide face defining an inner channel; a chamfered edge between said guide face and one of said longitudinal edges; said inner channel comprising an inlet portion and an outlet portion; the longitudinal contour of said inner channel from proximity to said inlet portion toward said outlet portion, consisting of a series comprising a guide face portion extending substantially to one longitudinal edge portion, a chamfered edge on the next succeeding convolution, substantially adjacent said last-mentioned longitudinal edge portion but spaced from said guide face portion, and the next succeeding guide face portion substantially extending from said chamfered edge portion substantially to the next succeeding longitudinal edge portion of said last-mentioned convolution.
